United States Patent Office

Des. 176,886
Patented Feb. 7, 1956

176,886

SANDAL

Thyra A. Russell, Woodland Hills, Calif.

Application May 19, 1955, Serial No. 36,120

Term of patent 7 years

(Cl. D7—7)

Fig. 1.

Fig. 2.

Fig. 3.

Fig. 1 is a front perspective view of the sandal showing my new design;

Fig. 2 is a top plan view thereof; and

Fig. 3 is a side view thereof.

I claim:

The ornamental design for a sandal, substantially as shown.
